UNITED STATES PATENT OFFICE

2,030,535

MINING MACHINE

Charles A. Pratt, Chicago, Ill., assignor to Goodman Manufacturing Company, Chicago, Ill., a corporation of Illinois

Application August 28, 1931, Serial No. 559,869

45 Claims. (Cl. 262—28)

This invention relates to improvements in mining machines and more particularly to a new and improved track-mounted mining machine adapted to cut a kerf adjacent the mine bottom in front of the mine rails or at various elevations with respect thereto.

My invention has as one of its objects to provide a new and improved mining machine of the class described particularly adapted for use in restricted places such as mine entries and arranged to cut a kerf across a coal face while the machine is held in a stationary position on the track, which kerf may have a substantially straight inner face.

Other objects of my invention will appear from time to time as this specification proceeds.

My invention may be more clearly understood with reference to the accompanying drawings wherein:

Figure 1 is a top plan view of a machine constructed in accordance with my invention with parts broken away and in section to more clearly show the details thereof;

Figure 2 is a fragmentary side elevation of the rearward portion of the device shown in Figure 1 with parts broken away and in section;

Figure 3 is a fragmentary side elevation of the forward portion of the device shown in Figure 1 with parts broken away and in section to more clearly show the details of the feeding and cutter chain driving mechanism;

Figure 4 is a fragmentary plan view of the forward portion of the device shown in Figure 1 with parts broken away and in section showing the details shown in Figure 3 in plan elevation;

Figure 5 is a partial fragmentary plan view of the rearward portion of the device shown in Figure 1 with parts broken away and in section to more clearly show the details of the truck drive;

Figure 6 is an enlarged partial fragmentary detail view of the forward portion of the device shown in Figure 1 showing certain details of the feed drive mechanism;

Figure 7 is an enlarged sectional view taken on line 7—7 of Figure 4;

Figure 8 is a partial fragmentary detail plan view of the forward portion of the device with parts broken away and in section showing certain details of the cutting mechanism supporting device;

Figure 9 is a sectional view taken on line 9—9 of Figure 8;

Figure 10 is a sectional view taken on line 10—10 of Figure 8;

Figure 11 is a detail plan view of the forward

portion of the embodiment of my invention illustrated with parts broken away and in section;

Figure 12 is a partial fragmentary side elevation of the forward portion of the embodiment of my invention illustrated showing the control levers therefor;

Figure 13 is a sectional view taken substantially on line 13—13 of Figure 11;

Figure 14 is an enlarged detail partial sectional view of one of the controlling levers;

Figure 15 is an enlarged partial sectional view showing the details of certain of the brake operating means; and

Figures 16 to 22, inclusive, are diagrammatic views showing the operation of the embodiment of my invention illustrated in Figure 1.

Like numerals refer to like parts throughout the various figures.

Referring now in particular to the drawings, the embodiment of my invention illustrated includes a main or truck frame 11 mounted on track wheels 12 and axles 13 and having a cutting element, generally indicated at 14, supported thereon for transverse movement across the forward end thereof and pivotal movement with respect thereto.

The truck frame 11 supports suitable power means for operating the cutting element 14 and driving the truck on its track wheels about the mine, which power means may be of any well known type, but is herein preferably shown as being an electric motor 15 of a usual construction.

The electric motor 15 has operative connection with the track wheels 12 for driving said track wheels through a motor pinion 16 which meshes with and drives a spur gear 17 keyed on a longitudinally extending stub shaft 18. A spur pinion 19 is keyed on the opposite end of said stub shaft and meshes with and drives a spur gear 21 on a longitudinally extending shaft 22. A bevel gear 23 is keyed on the opposite end of the shaft 22. This bevel gear meshes with and drives bevel gears 24 on opposite sides thereof freely mounted on a transversely extending shaft 25. Clutch jaws 26 are formed integral with the inner face of the bevel gears 24. Said clutch jaws are adapted to be engaged by clutch jaws 27 on a clutch collar 28 which is feathered on the transversely extending shaft 25 so said shaft may be driven in opposite directions without reversal of the motor 15 in the usual manner.

A sprocket 29 is keyed on the outer end of the transversely extending shaft 25 and has driving connection with the rearward truck axle 13 by means of a suitable chain and sprocket drive in-

10

dicated at 30. The forward and rearward truck axles 13 are connected together by suitable chain and sprocket drives, generally indicated at 31.

A suitable braking device is provided for braking the mining machine when desired and holding said mining machine in a stationary position on the track during the cutting operation. Said braking device may be of any suitable construction but is herein preferably shown as comprising 10 a brake drum 32 keyed on the transversely extending shaft 25 and adapted to be engaged by a brake band 33 through a suitable system of levers in a usual manner.

Referring now in particular to the means for 15 supporting the cutting element 14 on the truck frame 11 for transverse movement therealong and pivotal movement with respect thereto, a transversely extending guide member 35 is provided on the truck frame 11 adjacent the forward 20 end thereof. Said transversely extending guide member is pivotally supported adjacent its upper side on a transversely extending shaft 37 supported on a forward vertical wall of a frame member 36. Said transversely extending shaft is 25 supported intermediate its ends in the frame member 36 and its ends are journaled in suitable lugs integral with and extending rearwardly of the transversely extending guide member 35. Said shaft forms a support for said transversely 30 extending guide member (see Figure 8).

Means are provided to move the transversely extending guide member 35 about the axis of the transverse shaft 37 which herein comprise a pair of threaded members 38 disposed on opposite 35 sides of the frame member 36 (see Figures 1 and 3). Said threaded members are threaded within the hubs of worm gears 39 journaled in housings 40. The worm gears 39 mesh with and are driven from worms 41 fixed on a transversely extending 40 shaft 42. Said transversely extending shaft may be driven in any manner well known to those familiar with the art; as, for instance, a hand crank (not herein shown) adapted to fit on a squared end of said shaft.

45 A collar 43 is provided adjacent the forward end of the threaded portion of each threaded member 38. A compression spring 44 encircles each of said threaded members and abuts the collar 43 at one of its ends. The opposite end of 50 each of said compression springs fits on a lug 35a extending rearwardly from the transversely extending guide member 35 and engages the rearward side of said transversely extending guide member. Thus, a yieldable means has been provided for supporting the transversely extending 55 guide member 35 and cutting element 14. It may thus be seen that rotation of the transversely extending shaft 42 drives the worm gears 39 which moves the transversely extending guide 60 member 35 about the axis of the shaft 37 through the compression springs 44 to form a means for adjusting the angle of the cutting element 14 with respect to the mine bottom, and that the compression springs 44 form a yieldable support for 65 the cutting mechanism and serve to counteract the effect of the forces imparted to the truck frame 11 by the cutting element 14 during the cutting operation due to irregularities in the coal seam.

70 The transversely extending guide member 35 comprises a fixed central portion 47 and hinged outer portions 48. Some of the purposes in hinging the outer ends of the transversely extending guide member 35 are to make it possible to position the hinged outer portions of said guide mem-

ber along the truck frame 11 and keep the width of the mining machine to a minimum while traveling and to make it possible to cut a kerf in a relatively narrow entry when desired which may require one outer end extended and the other folded; as, for example, where the working face is wide, both of the outer ends 48 may be locked in an extended position, but where the working face is narrow, one or the other, or both of the outer ends 48, may be folded along the 10 sides of the machine making it possible to effectively cut in working places of varying widths.

In looking at Figures 8, 9 and 10, which show the details of the means for supporting the hinged outer portions 48 on the central portion 15 47, it may be seen that a hinge member 49 is secured to the inner end of the outer portions 48 of the transversely extending guide member 45. This hinge member extends rearwardly and inwardly from each outer portion 48 of the guide 20 member 35 and is adapted to be engaged adjacent its top and bottom sides by ears 50 secured to the outer ends of the central portion 47 of the transversely extending guide member 35 and extending rearwardly and outwardly therefrom. A 25 shaft 52 extends through the ears 50 and the hinge member 49 for securing the hinged outer portions 48 to opposite ends of the central portion 47 and allowing said hinged outer portions to be pivotally moved with respect to said central portion.

Means are provided for locking the hinged outer portions 48 in alignment with the central portion 47, which means herein comprise a pin 53 adapted to pass through each ear 50 and hinge 35 member 49. Likewise, additional locking means are provided to lock the hinged outer portions 48 in alignment with the central portion 47 and also aid in supporting said hinged outer portions when locked in alignment with said central portion. 40 Said means herein comprises a sector plate 54 integral with each hinged outer portion 48 and extending inwardly therefrom. Each sector plate 54 is adapted to slide in a guide groove 55 formed in the lower outer ends of the central portion 47. 45 A pin 56 is provided for locking the sector plate 54 in alignment with the central portion 47 of the transversely extending guide member 35.

It should herein be noted that the transversely extending guide member 35 is L-shaped, having 50 its base extending forwardly from the truck frame 11, and that the guide grooves 55 are formed in the base of the L of the central portion 47 and that the sector plate 54 is formed integral with the base of the L of the hinged outer portions 48, 55 which construction provides a rigid support for the cutting element 14.

Thus the truck frame 11 has been provided with an adjustable guide member extending transversely across the forward end thereof for supporting the cutting element 14 for movement therealong, which guide member may be locked in an extended position with respect to said truck or may be folded against the side of said truck. It may also be seen that said guide member is supported for yieldable movement about a horizontal transverse axis and forms a means for yieldably adjusting the angle of the cutting element with respect to the mine bottom, which provides yieldability in the cutting element to compensate for 70 irregularities in the material to be cut.

Referring now in particular to the cutting element and means for supporting said cutting element on the guide member 35, said cutting element comprises a cutter head 57 supported on said 75

guide member for movement therealong as has hereinbefore been mentioned. Said cutter head serves to house the cutting element drive gearing and the mechanism for feeding said cutter head and cutting element transversely across said transverse guide member.

A portion 58 of the cutter head 57 extends rearwardly therefrom over and around the guide member 35 and has engagement with the rearward side 10 thereof (see Figure 3). Suitable rollers 59 are provided in the portion 58 of said cutter head to engage the rearward side of said guide member and reduce the friction between said cutting element and said guide member upon movement of 15 said cutting element therealong. The lower rearward side of said cutter head has bearing engagement with the forward side of the transversely extending guide member 35 while rollers 60 extend downwardly from the cutter head 57 and have 20 bearing engagement with the top side of the base of the L of the transversely extending guide member 35. Likewise, a portion 61 extends downwardly from the cutter head 57. This portion of the cutter head 57 is provided with a guide groove 25 62, which engages a gib 63 extending downwardly from the forward side of the base of the L which forms the transversely extending guide member 35. Thus a rigid support has been provided for the cutter head 57 so said cutter head may be 30 moved along the transversely extending guide member 35 during the cutting operation.

The cutter head 57 serves to support a cutter bar 64 for vertical movement with respect thereto in parallel spaced depending guides 65. Said 35 parallel spaced depending guides are disposed on opposite sides of the cutter head 57 forwardly of the transversely extending guide member 35 but rearwardly of the major portion of the cutter head 57.

40 Referring now in particular to the cutter bar 64 and the method of supporting said cutter bar in the parallel spaced depending guides 65 for vertical movement with respect to the cutter head 57 and for movement about a vertical axis, said 45 cutter bar is provided with a cutter chain 66 which is movable thereabout in a usual manner. The parallel spaced depending guides 65 are provided with forwardly extending gibs 67 which are engaged by grooves 68 formed in arms 69 extending 50 rearwardly outwardly from an annular shaped support member 70. Retaining strips 69a are secured to the rearward side of the arms 69 and about the rearward side of the depending guides 65 for holding the annular shaped support member 70 to the guides 65 for movement therealong.

55 The annular shaped support member 70 is adapted to support a cutter bar supporting member 71, which extends rearwardly from the cutter bar 64.

60 The cutter bar supporting member 71 has bearing engagement with the inner periphery of the annular shaped support member 70 and with the lower and outer sides of said annular shaped support member and has an internal gear 72 cut in 65 its inner periphery. An annular ring 73 is secured to the top outer portion of the cutter bar supporting member 71 in a usual manner and engages a shoulder 74 in the top outer portion of the annular shaped support member 70 for 70 holding said cutter bar supporting member to said annular shaped support member for pivotal movement with respect thereto.

75 A pinion 75 is preferably shown as being integral with the lower end of a threaded shaft 76. Said threaded shaft is journaled in and ex-

tends upwardly from the annular shaped support member 70 so as to be fixed from vertical movement with respect thereto. Said pinion is rotatable in an opening 77 in the annular shaped support member 70 and meshes with the internal gear 72 for pivotally moving said cutter bar supporting member upon rotation of the threaded shaft 76.

The threaded shaft 76 has its upper portion threaded within the hub of a worm gear 79, which 10 worm gear is journaled in the forward end of the cutter head 57. Keyways 80 are provided in opposite sides of the threaded shaft 76 and are adapted to be engaged by feather keys 81 in a collar 82 disposed above the worm gear 79. Clutch 15 jaws 83 are provided on the top face of said worm gear and are adapted to be engaged by clutch jaws 84 depending from the collar 82 for rotating said collar and said threaded shaft. This pivotally moves the cutter bar supporting member 71 20 and cutter bar 64 about the annular shaped support member 70. Suitable means are provided to engage the clutch jaws 84 with the clutch jaws 83, which means are of an ordinary construction well known to those familiar with the art so are 25 not herein described or shown in detail.

It may now be seen that upon rotation of the worm gear 79 when clutch jaws 84 engage the clutch jaws 83, the cutter bar 64 is pivotally moved about a vertical axis and when the clutch 30 jaws 84 are disengaged from the clutch jaws 83, the cutter bar 64 is moved towards or away from the cutter head 57 depending upon the direction of rotation of the worm gear 79.

The worm gear 79 is driven by a worm 85 on a 35 longitudinally extending shaft 86, which shaft in turn is driven from the motor 15 at a plurality of frictionally controlled speeds in reverse directions without reversal of said motor in a manner which will hereinafter be more fully described. 40 Said worm gear and worm are of the self-locking type so the cutter bar 64 may be locked in a fixed position when the clutch jaws 84 engage the clutch jaws 83 and the worm 85 is immobile. Thus the cutter bar 64 may be moved in a locked position 45 transversely across the face of the truck frame 11 in any desired angular position of said cutter bar with respect to said truck frame. It should be noted that while a self-locking worm and worm gear is herein utilized for locking the cutter bar 50 64 in fixed relation with respect to the cutter head 57, that any other well-known form of locking means may be used.

Referring now in particular to the means for driving the cutter chain 66 about the cutter bar 55 64, a sleeve 87 is journaled within the cutter bar supporting member 71 and is shouldered so as to abut the underside of said cutter bar supporting member. Said sleeve is provided with another shoulder for supporting a cutter chain drive 60 sprocket 88, which sprocket meshes with and drives the cutter chain 66. A collar 89 is threaded on the top portion of the sleeve 87 and abuts an internal shoulder in the cutter bar supporting member 71 for holding said sleeve within said 65 cutter bar supporting member.

The inner periphery of the sleeve 87 is provided with a plurality of grooves adapted to be engaged by a splined shaft 90. Said splined shaft extends upwardly from said sleeve and passes 70 through a vertically extending sleeve 91 journaled within the cutter head 57.

Another vertically extending splined shaft 93 has driving engagement with a hollow central portion of the splined shaft 90. Said splined shaft 75

is provided with a clutch collar 94 at its upper end, which has clutch jaws 95 depending therefrom and engageable with clutch jaws formed in a flange 96 extending outwardly from the top portion of the vertically extending sleeve 91 (see Figure 3). The jaws 95 of the clutch collar 94 are engaged with or disengaged from the jaws formed in the flange 96 of the vertically extending sleeve 91 by means of a suitable system of levers 10 in a usual manner not herein shown or described since it is no portion of my invention.

The vertically extending sleeve 91 is keyed to a bevel gear 97 near its upper portion, which bevel gear is journaled on its hub in the top portion of the cutter head 57 and is driven by a bevel pinion 98 keyed on the forward end of a shaft 99 journaled within a movable support member 100.

Thus when the vertically extending sleeve 91 is driven from the bevel gear 97 the cutter chain sprocket 88 may be driven from the clutch collar 94, vertically extending splined shaft 93 and splined shaft 99 and said splined shafts are so arranged as to compensate for vertical movement of said cutter bar with respect to said cutter head 25 in an obvious manner.

Referring now in particular to the means for driving the shaft 99 from the motor 15, the movable support member 100 bears on the top face of the bevel gear 97 and is journaled on the vertically extending sleeve 91 beneath the flange 96 for pivotal movement thereabout (see Figure 3). Said movable support member extends rearwardly from said vertically extending sleeve and is provided with an open rearward portion 35 adapted to slidably engage opposite sides of a pivotally movable bearing support member 101 (see Figures 1 and 2). Said pivotally movable bearing support member has bearing engagement with the top portion and end of a rearwardly extending horizontal portion of the frame 40 member 36 and extends rearwardly from the movable support member 100 and is provided with a weighted base 102 and an upright portion 103 forwardly of said weighted base and connecting said weighted base with the forward portion 45 of said pivotally movable bearing support member. The upright portion 103 is journaled on a vertically extending bearing member 104 fixed on the top side of the truck frame 11 and having a rearwardly extending portion 105 which is 50 provided with parallel spaced arcuate shaped bearing strips 106 on its upper surface. Said bearing strips are adapted to be engaged by said weighted base so said base may be moved across the portion 105 of the vertical bearing member 55 104.

Suitable means are provided to reduce the friction between the weighted base 102 and the bearing strips 106, which means herein comprises a plurality of balls 107 mounted in the under side of the weighted base 102 in a usual manner well known to those skilled in the art. Said balls have bearing engagement with the top side of the rearwardly extending portion 105 of the vertically extending bearing member 104.

It may thus be seen that the movable support member 100 and pivotally movable bearing support members 101 are so arranged that when the cutter head 57 is moved along the transversely extending guide member 35, the movable support member 100 moves with said cutter head and slides along and pivots the pivotally movable bearing support member 101 about its axis of pivotal connection to the truck frame 11. As said pivotally movable bearing support member

is moved about its axis of pivotal connection to said truck frame, said weighted base is moved in a direction opposite to the direction of movement of the cutter head 57 to counterbalance said cutter head.

A universal coupling 109 of an ordinary construction is secured to the rearward end of the shaft 99 and has a shaft 110 secured thereto and extending rearwardly therefrom. An internal splined sleeve 111 is secured to the shaft 110 and extends rearwardly therefrom and is adapted to be slidably engaged by and driven from a splined shaft 112 keyed to and driven from a bevel gear 113 journaled in the pivotally movable bearing support member 101. Thus the splined shaft 112 telescopes within the sleeve 111 upon movement of the cutting element 14 along the transversely extending guide member 35 and forms in effect a telescopic connection between the motor 15 and the cutter chain and feeding 20 drive mechanism.

A bevel gear 114 meshes with the bevel gear 113 for driving said bevel gear and is journaled in the upper portion of the vertically extending bearing member 104. The bevel gear 114 is keyed to the upper end of a vertical shaft 115 and a bevel gear 116 is keyed to the lower end of said vertical shaft and journaled on its hub within the lower portion of the vertically extending bearing member 104. The bevel gear 116 is driven from a bevel gear 117, which bevel gear is driven from the pinion 16 and the motor 15 by means of a suitable system of reduction gears indicated at 118 (see Figs. 1, 2 and 5). It may thus be seen that the arrangement of parts for driving the bevel gear 97 from the motor 15 is such that said bevel gear may be driven from said motor in all positions of the cutting element 14 along the transversely extending guide member 35.

Referring now in particular to the means for driving the worm 85 from the motor 15 in reverse directions without reversal of said motor at a plurality of predetermined frictionally controlled speeds and the means for moving the cutting element 14 along the transversely extending guide member 35, a bevel gear 120 is keyed to the lower end of the vertically extending sleeve 91 and is journaled in its hub in the cutter head 57 (see Figure 3). Said bevel gear meshes with and drives a bevel gear 121 keyed on a stub shaft 122 journaled in a bearing support 123 extending upwardly from and integral with the lower inside portion of the cutter head 57. A spur gear 124 is keyed on the opposite end of the stub shaft 122 and meshes with and drives an idler gear 125 freely mounted on the longitudinally extending shaft 86 at one side thereof. Said idler gear meshes with a spur gear 125a keyed on a longitudinally extending sleeve 126. The spur gear 124 meshes with and drives an idler gear 127 on its opposite side which meshes with and drives a spur gear 127a keyed on a longitudinally extending sleeve 128 (see Figures 4 and 7). The longitudinally extending sleeve 126 is freely mounted on a longitudinal shaft 129 and is journaled within the hub of a casing 130 for a planetary gear reduction device 131. The hub of said casing is in turn journaled in a bearing support 133 extending upwardly from the bottom portion of the cutter head 57.

The planetary gear reduction device 131 is of a usual type well known to those familiar with the art, and as herein shown comprises a sun gear 75

134 cut integral with the inner end of the longitudinally extending sleeve 126 which meshes with and drives planetary pinions 135 journaled in a cage 136 (see Figure 6). The planetary pinions 135 are meshed with an internal gear 137 fixed to the inner periphery of the casing 130. Planetary pinions 139 are cut integral with planetary pinions 135 and are disposed to one side of said planetary pinions. The planetary pinions 139 mesh with an internal gear 140 keyed to the inner surface of a member 141 having a rearwardly extending hub 142 thereon journaled within a bearing support 143 extending upwardly from the bottom portion of the cutter head 57.

15 Suitable means are provided for holding the casing 130 from rotation or allowing said casing to rotate upon overload of the planetary gear reduction device 131. Said means herein comprise a friction band 144 adapted to be engaged with the outer surface of the casing 130. Said friction band has a lug 145 thereon. A suitable spacing block is secured to the top portion of the lug 145 and is adapted to abut the under surface of an angle 146 secured to the inner surface of the cutter head 57. The opposite end of the friction band 144 has a lug 147 thereon. A threaded rod 148 passes through said lugs and has a nut 149 threaded thereon abutting the underportion of the lug 147. The upper end of the threaded rod 148 is pivotally supported on a lever arm 150 keyed on a transversely extending tubular shaft 151. Said transversely extending tubular shaft has its ends journaled in opposite sides of the cutter head 57 and has hand levers 152 keyed to opposite sides thereof so said transversely extending tubular shaft may be operated from either side of the cutter head 57. (See Figs. 11 to 14, inclusive.)

40 Means are provided for locking each of the hand levers 152 in a fixed position with respect to the cutter head 57 and holding the friction band 144 in engagement with or disengagement from the casing 130, which means herein comprise a pin 153 which passes through the hand lever 152 and is adapted to engage one of a number of apertures 154 in the outer surface of the cutter head 57. Said pin is engaged with said apertures by means of a lever 155 pivoted on the hand lever 152 intermediate its ends and having engagement with said pin at its opposite end.

45 Means are also provided wherein the hand levers 152 may be unlocked from one side or the other of the cutter head 57. Said means herein comprises a separate lever arm 156 pivotally connected at one of its ends with the outer end of each pin 153 and pivotally supported on each hand lever 152 intermediate its ends. A rod 157 is pivotally supported on the opposite end of the lever arm 156 and extends through the transversely extending tubular shaft 151 and has suitable gripping means on its end so movement of said rod will cause movement of the pin 153 in an obvious manner. It may thus be seen that the hand lever 152 on one side of the machine 50 may be unlocked by operation of the lever 155 pivotally supported on said hand lever, or may be unlocked by operation of the rod 157 from the opposite side of the cutter head 57.

55 When the friction band 144 is engaged with the casing 130, the internal gear 137 will remain stationary and the planetary pinions 135 will rotate within said internal gear. This will cause the rotation of the cage 136 and rotation of the planetary pinions 139 which will drive the internal gear 140 and the member 141. When an ex-

cess load is imparted to either the member 141 or the cage 136, the friction band 144 will tend to slip which will decrease the speed of rotation of said internal gear and cage.

60 Means are provided to connect either the internal gear 140 or the cage 136 with the longitudinal shaft 129 for driving said shaft at either a high or low frictionally controlled speed. Said means herein comprise a clutch collar 159 feathered on the longitudinal shaft 129 and having 10 clutch jaws 160 on its forward end. Said clutch jaws are adapted to engage clutch jaws 161 connected with the cage 136 for driving the longitudinal shaft 129 at a relatively high frictionally controlled speed, or clutch jaws 163 extending 15 inwardly from the hub 142 of the member 141 for driving the longitudinal shaft 129 at a relatively low frictionally controlled speed.

20 The clutch collar 159 is moved along the longitudinal shaft 129 to engage the clutch jaws 160 with either the clutch jaws 161 or 163 by means of a suitable system of levers which herein comprise a clutch yoke 164 having engagement with said clutch collar and operated by a clutch fork 165 fixed on a transversely extending tubular 25 shaft 166. Hand levers 167 are fixed on opposite ends of the transversely extending tubular shaft 166 for operating said shaft from either side of the cutter head 57. Suitable locking means are provided for locking the hand levers 167 in a 30 fixed position to hold the clutch jaws 160 in engagement with the clutch jaws 161 or 163. These locking means are the same as provided to lock the hand levers 152 and may be unlocked from either side of the cutter head 57 in the same manner the hand levers 152 may be unlocked from either side of said cutter head.

35 A spur pinion 169 is keyed on the longitudinal shaft 129 adjacent the rearward end of the clutch collar 159. Another spur pinion 170 is keyed on the rearward end of the longitudinal shaft 129. The spur pinion 169 meshes with and drives an idler gear 172 which in turn meshes with and drives a spur gear 171 freely mounted on the longitudinally extending shaft 86. The spur 40 pinion 170 meshes with and drives a spur gear 173 in a direction opposite to which the spur gear 171 is driven. Suitable clutch means are provided for interconnecting either the spur gear 171 or the spur gear 173 with the longitudinally extending shaft 86 for driving said shaft in opposite directions without reversal of the motor 15. This clutch means may be of any type well known to those skilled in the art but is herein preferably shown as being a cone clutch 174 of an ordinary 45 construction feathered on the longitudinally extending shaft 86 for connecting the spur gear 171 with the longitudinally extending shaft 86 and a cone clutch 175 for connecting the spur gear 173 with the longitudinally extending shaft 86. The 50 cone clutches 174 and 175 are connected together by a suitable clutch collar so the transversely extending shaft 86 cannot be driven by the spur gears 171 and 173 simultaneously and are shifted by means of a clutch yoke 176 operatively connected with a shifting fork 177 secured to a transversely extending tubular shaft 178. Said tubular shaft is journaled at its ends in the cutter head 57 and is operated by suitable levers and locking mechanism at opposite sides thereof so 55 either the cone clutch 174 or 175 may be connected with its respective spur gear 171 or 173 for driving the longitudinally extending shaft 86 in opposite directions without reversal of the motor 15. 60

It may thus be seen that the threaded shaft 76 may be selectively driven from the motor 15 in opposite directions without reversal of said motor for either moving the cutter bar toward or away 5 from the cutter head 57 or for reversely pivotally moving said cutter bar about the axis of the splined shaft 90 depending on whether the clutch jaws 83 are engaged with or disengaged from the clutch jaws 84.

Referring now in particular to the means for moving the cutting element 14 along the transversely extending guide member 35, a portion 179 of said guide member extends forwardly therefrom adjacent the upper side thereof and has a 10 rack 180 secured thereto and depending therefrom. A spur pinion 181 is keyed on the rearward end of a longitudinal shaft 183 and meshes with the rack 180 so rotation of said pinion in one direction or the other will move the cutter head 57 and cutting element 14 across said transversely extending guide member in one direction or the other. Said longitudinal shaft is journaled in the cutter head 57 and is driven from either a friction cone clutch 184 or friction cone 15 clutch 185 feathered on said shaft. The friction cone clutch 184 has connection with a spur gear 186 for driving said longitudinal shaft in one direction while the friction cone clutch 185 is adapted to engage a spur gear 187 for driving said 20 longitudinal shaft in an opposite direction.

The friction cone clutch 184 or 185 is engaged with its respective spur gear 186 or 187 for driving the longitudinal shaft 183 in opposite directions without reversal of the motor 15 25 by means of a suitable system of levers connected with a transversely extending tubular shaft 188. Said tubular shaft is operated by a suitable system of levers and locked in its various operative positions by suitable locking means similar to that used for operating and locking the transversely extending tubular shaft 151 so will not 30 herein be described in detail.

The spur gear 186 is driven from a longitudinal shaft 189 by means of a spur pinion 190 while the 35 spur gear 187 is driven from the longitudinal shaft 189 by means of an idler gear 191 and spur pinion 192. The longitudinal shaft 189 extends through and is driven from a suitable frictionally controlled planetary gear reduction device 193, 40 which planetary gear reduction device is driven by the spur gear 127a secured to the longitudinal sleeve 128 in a usual manner. Said planetary gear reduction device is controlled by means of a suitable friction band 194 which is operated by a 45 suitable system of levers in the same manner the friction band 144 is engaged with or disengaged from the casing 130. Said planetary gear reduction device is of the same construction as the planetary gear reduction device 131 so will not 50 herein be described in detail. A clutch collar 195, operated by a suitable system of levers in the same manner the clutch collar 159 is operated, is provided to connect the planetary gear reduction device 193 with the longitudinal shaft 189 55 for driving said shaft at either a high or low frictionally controlled speed.

Thus when the planetary gear reduction device 193 is connected with the shaft 189 for driving 60 said shaft at a high or low frictionally controlled speed and either one or the other of the gears 186 or 187 is operatively connected with the shaft 183, the cutting element 14 may be moved across the transversely extending guide member 35 in 65 one direction or the other without reversal of the

motor 15 at either a high or low frictionally controlled speed.

It may be understood with reference to Figures 16 to 21, inclusive, that when cutting narrow places it is desirable that the cutter bar 64 be 5 pivotally moved about the axis of the splined shaft 90 as the cutting element 14 is moved transversely along the transversely extending guide member 35 in order to sump said cutter bar into the coal and withdraw said cutter bar 10 from the coal upon completion of the cut across the coal face as the machine itself is in a stationary position on the track. As has before been described, pivotal movement of the cutter bar is controlled by the planetary gear reduction 15 device 131 and the cone clutches 174 and 175, while transverse movement of the cutting element 14 along said guide member is controlled by the planetary gear reduction device 193 and the cone clutches 184 and 185. Each of these 20 planetary gear reduction devices and each pair of cone clutches is operated by a separate lever and the gear reduction is such that under ordinary conditions the rate of pivotal movement of the cutter bar with respect to transverse movement of said cutter bar is so timed that it will be uniformly sumped into the material to be cut as the cutting element 14 is moved along the transversely extending member 35. In case hard 25 spots are encountered in the coal, causing undue 30 loads to be placed on the cutter bar and feed drive mechanism, the friction band 144 will slip on the casing 130 of the planetary gear reduction device 131 to slow down pivotal movement of the cutter bar 64, and the friction band 194 will slip 35 on the casing of the planetary gear reduction device 193 to slow down transverse movement of the cutting element 14 along said guide member 35. While the cutter bar is pivotally moved about the axis of the splined shaft 90 simultaneously 40 with transverse movement of said cutter bar, the drive mechanisms for effecting this simultaneous and pivotal movement are not shown as being connected or operated together since there are 45 times during the operation of the machine when it is desired that the cutter bar be moved transversely across the guide member 35 only, or be independently pivotally moved about a vertical axis. It may therefore be seen that it is preferable that the planetary gear reduction devices 50 131 and 193 and the pairs of friction cone clutches 174 and 175, and 184 and 185 be operated independently of each other. It is apparent that adjustment of the transverse speed of travel of the cutting element 14 or the rotational speed of the cutter bar about the axis of the shaft 90 may be manually accomplished by exerting more or less pressure on the friction bands for the respective planetary gear reduction devices through the medium of the respective 55 hand levers as has hereinbefore been fully explained.

In Figure 16 the mining machine is being moved into an entry in position to make a cut across the face of the entry perpendicular to 65 and in front of the end of the track. The hinged outer portions 48 of the guide member 35 are positioned parallel to the sides of the truck frame. In Figure 17 the hinged outer portions 48 of said guide member have been locked in aligned 70 position and the cutting element 14 is shown as positioned to one side of said guide member, and the cutter bar is shown as extending parallel with said guide member. The machine is then moved forwardly along the rail on the track wheels 12 75

until said cutter bar may be adjusted to a position beneath the mine rails by means of the threaded shaft 76 or to any level at which it is desired to cut. When said cutter bar is in such a position, the cutter chain 66 is put in motion and said cutting element is moved along said transversely extending guide member. Said cutter bar is simultaneously moved about a vertical axis and sumped into the face of the material to be cut, the cutting machine itself being held in a stationary position on the track by means of the brake band 33 engaged with the brake drum 32 or by means of wedges inserted behind the track wheels or jacks interposed between the mine roof and machine frame in a usual manner well known to those skilled in the art.

When the cutter bar has been sumped to the desired depth, pivotal movement of the cutter bar about a vertical axis may be stopped and the cutter bar locked in a fixed position with respect to the cutter head by means of the self-locking worm 85 and worm gear 79. Said cutter bar then may be moved transversely across the face of the coal a distance depending upon the width of the place to be cut. The direction of movement of the cutting element along said guide member is then reversed and said cutter bar is again pivotally moved about the axis of the splined shaft 90. This withdraws said cutter bar from the material to be cut, said cutter bar cutting out the uncut material as it is being withdrawn, and leaves the face of the coal completely undercut. This cutting movement described effects a cut having a substantially straight face at the inside of the kerf in a place of substantially the same width as said guide, as is illustrated by Figures 20 and 21.

When the cutter bar has been completely withdrawn from the coal and is in a position substantially parallel to said guide member, it may be raised above the level of the mine rails and the mining machine may be backed along said rails on the track wheels 12. Said cutter bar and guide member are then positioned as shown in Figure 16 and the machine is ready to travel to a new working place.

Inasmuch as said cutting element may be moved along the guide member 35 in reverse directions without reversal of the motor at either a high or low frictionally controlled speed independently of pivotal movement of the cutter bar, and inasmuch as said cutter bar may be pivotally moved in reverse directions without reversal of said motor at either a high or low frictionally controlled speed independently of movement of the cutter head 57 along said guide member, it may readily be seen that while the device of my invention is particularly adapted for use in narrow working places, it may also effectively cut in wide places and around obstructions in the coal seam.

One method in which the device of my invention may cut a wide place is clearly illustrated in Figure 22. In cutting a wide room there is a tendency for the machine to overbalance due to the fact that the cutting element is usually positioned in an extended position to one side of the machine frame during the initial cutting operation and the reaction due to cutting is on the same side of the machine frame. It is apparent that it would be impractical to construct the weighted base 102 of such size that its counter-balance effect would prevent the machine from overbalancing while cutting with the cutting element overhanging one side or the other

of the truck. The means herein shown for holding the machine to the track comprise suitable jacks, generally indicated by reference character 200, interposed between the truck frame 11 and the mine roof in an ordinary manner well known to those skilled in the art. After the machine has been jacked down by said jacks, and brake band 33 has been applied to the brake drum 32, the cutting element is moved to an overhanging position with respect to said main frame on the transversely extending guide member 35, the amount of overhang depending upon the width of the place to be cut. The cutter bar is then turned so its longitudinal center line is inclined rearwardly with respect to said guide member 15 and the cutter chain 66 is set in motion. The cutter bar is then rotatably moved about the axis of the shaft 90 and sumped into the coal until it has reached a position substantially perpendicular to said guide member. The cutter bar 20 is then locked in stationary position with respect to said cutter head and moved across said transversely extending guide member to the opposite end thereof. Movement of said cutting element along said guide member is stopped 25 when the ends of the cutter chain bits adjacent the forward end of the cutter bar are substantially adjacent the opposite rib and said cutter bar is positioned parallel with said guide member. The cutter bar is then pivotally moved 30 about the axis of the shaft 90 in the same direction as formerly until it has completely cut itself out of the coal. The cutting element 14 is then returned to a central position with respect to said guide member with the cutter bar in an elevated position with respect to the ground. The outer ends 48 of said guide frame are then folded along the sides of the truck frame and the machine is positioned for movement to the next working place.

It may now be seen that I have provided a new and improved track mounted mining machine and method of cutting in wide or narrow places while the machine proper is in a stationary position on the track; that this machine is 45 so constructed as to give a maximum amount of movement of the cutter bar in various directions and angles with respect to the machine proper in a plane substantially parallel to the mine bottom, permitting the cutter bar to cut 50 places of varying widths and more particularly to cut a relatively straight face in narrow places and readily cut out or around obstructions in the coal seam while the machine is in a stationary position on the track; and that all feeding or 55 positioning movements of the cutter bar are variable and under frictional control.

While I have herein shown and described one form in which my invention may be embodied, I do not wish to limit myself to the precise construction and arrangement of parts shown, it being understood that alterations or changes may be made without departing from the spirit and scope thereof. Furthermore, I do not wish to be construed as limiting myself to the particular embodiment illustrated, excepting as it may be limited in the appended claims.

I claim as my invention:

1. In a mining machine, a main frame, a transversely extending rectilinear guide member wholly supported by said main frame forwardly of the forward end thereof, and a chain carrying cutter bar wholly supported on said transversely extending guide member, said cutter bar being adapted to depend from said guide member and 75

mounted thereon for translational and pivotal movement with respect thereto.

5 2. In a mining machine, a main frame, a transversely extending rectilinear guide member wholly supported by said main frame forwardly of the forward end thereof, and a chain carrying cutter bar wholly supported on said transversely extending guide member, said cutter bar being adapted to depend from said guide member and 10 mounted thereon for simultaneous translational and pivotal movement with respect thereto.

15 3. In a mining machine, a main frame, a transversely extending rectilinear guide member wholly supported by said main frame forwardly of the forward end thereof, and a chain carrying cutter bar wholly supported on said transversely extending guide member, said cutter bar being adapted to depend from said guide member and 20 mounted thereon for independent translational or pivotal movement with respect thereto.

25 4. In a mining machine, a main frame, a transversely extending rectilinear guide member wholly supported by said main frame forwardly of the forward end thereof, and a chain carrying cutter bar wholly supported on said transversely extending guide member, said cutter bar being adapted to depend from said guide member and 30 mounted thereon for simultaneous or non-simultaneous translational and pivotal movement with respect thereto.

35 5. In a mining machine, a track mounted main frame, a transversely extending rectilinear guide member extending across the forward end of said main frame and wholly supported thereby, a cutter head mounted on said guide member and wholly supported thereon for movement therewith, and a chain carrying cutter bar carried by and depending from said cutter head and guide member and mounted for pivotal movement with 40 respect thereto independent of movement of said cutter head along said guide member.

45 6. In a mining machine, a track mounted main frame, a transversely extending rectilinear guide member extending across the forward end of said main frame and wholly supported thereby, a cutter head mounted on said guide member and wholly supported thereon for movement therewith, and a chain carrying cutter bar carried by and depending from said cutter head and guide 50 member and mounted for pivotal movement with respect thereto simultaneous with or independent of movement of said cutter head along said guide member.

55 7. In a mining machine of the class described, a track mounted main frame, a motor mounted on said main frame, a rectilinear guide member extending transversely across the forward end of said main frame and wholly supported thereby, a cutting element associated with said guide member for movement therewith including a projecting cutter bar, and self-contained plural speed means driven by said motor for moving said cutting element along said guide member and for independently moving said cutter bar about a vertical axis including a pair of independent plural speed gear reduction devices.

60 8. In a mining machine, a truck, a motor on said truck, a guide member wholly supported by and extending across the forward end of said truck, an elongated cutting element associated therewith and adapted to revolve about an axis located near one end of said cutting element, means for revolving said cutting element about said axis, and self-contained means driven by said 65 motor for moving said cutting element along said

guide member in reverse directions while said cutting element is revolving about said axis in one direction.

9. In a mining machine, a truck, a guide member wholly supported by and extending across the forward end of said truck, a motor on said truck, a cutting element associated with said guide member and adapted to revolve about a center located near one end of said cutting element, self-contained means driven by said motor for revolving said cutting element about said center of rotation, and other self-contained means driven by said motor for moving said cutting element along said guide member in reverse directions without reversal of said motor while said cutting element is revolving in one direction. 10 15

10. In a mining machine, a truck, a guide member wholly supported by and extending across the forward end of said truck, a motor on said truck, a cutting element associated with said 20 guide member and adapted to revolve about a center located near one end of said cutting element, self-contained means driven by said motor for moving said cutting element along said guide member in reverse directions without reversal of 25 said motor, and other self-contained means driven by said motor for independently revolving said cutting element in reverse directions without reversal of said motor.

11. In a mining machine, a truck, a motor on 30 said truck, a guide member wholly supported by and extending across the forward end of said truck, a cutting element associated therewith and adapted to revolve about a center located near one end of said cutting element, self-contained 35 means driven by said motor for revolving said cutting element about said center of rotation, and other self-contained means driven by said motor for moving said cutting element along said guide member in reverse directions while said cutting 40 element is revolving in one direction including reverse gearing.

12. In a mining machine, a body, a guide supported by and extending transversely across one end of said body, an elongated cutting element 45 wholly supported on said guide including a cutter head slidably supported on said guide and a cutter bar carried thereby for pivotal movement with respect thereto about a vertical axis, and self-contained means for swinging said cutter 50 bar about a vertical axis and moving said cutter bar along said guide so its longitudinal center line lies at substantially right angles to the longitudinal center line of said body, and the extended center line of said body crosses the center line of 55 said cutter bar between the ends of the latter when said cutter bar is at one end or the other of said guide comprising a motor on said body and a pair of independently operable gear reduction devices interposed between said motor and 60 cutter head.

13. In a mining machine, a body, a motor, a guide supported by and extending transversely across one end of said body, an elongated cutting element wholly supported on said guide, means for so positioning said cutting element with respect to said guide that its longitudinal center line lies at substantially right angles to the longitudinal center line of said body, and the extended longitudinal center line of said body crosses the 70 center line of said cutting element between the ends of the latter, and means driven by said motor for moving said cutting element to cause said extended longitudinal center line of said body to approach one end or the other of said cutting 75

element without reversal of said motor comprising a pair of independently operable gear reduction devices interposed between said motor and cutting element including reverse gearing.

5 14. In a mining machine, a body, a motor, a guide extending transversely across one end of said body, an elongated cutting element wholly supported on said guide, means for so positioning said cutting element with respect to said guide 10 that its longitudinal center line lies at substantially right angles to the longitudinal center line of said body, and the extended longitudinal center line of said body crosses the longitudinal center line of said cutting element between the ends 15 of the latter, a gear train including reverse gearing driven by said motor for moving said cutting element to cause said extended longitudinal center line of said body to approach one end or the other of said cutting element without reversal of 20 said motor, and another gear train driven by said motor for changing the angular relation of said center lines with respect to each other.

25 15. In a track mounted mining machine, a truck frame having track wheels and axles thereon, a guide extending transversely across the forward end of said truck frame and wholly supported thereby, an elongated cutting element associated with and wholly supported by said guide for movement therealong and for pivotal movement 30 with respect thereto, means for supporting said cutting element for adjustment above the level of the track in a vertical direction in a plurality of parallel planes for transportation and cutting above the mine bottom and below the 35 level of the track for cutting along the mine bottom comprising an extensible adjusting member arranged in parallel relation with respect to the axis of pivotal movement of said cutting element.

40 16. In a mining machine of the class described, a track mounted main frame, a transversely extending guide member supported forwardly of said main frame, a cutting element associated with said guide member for movement therealong including a projecting cutter bar, and self-contained plural speed frictionally controlled means driven by a motor on said main frame for moving said cutting element along said guide member and independently moving said cutter bar about a vertical axis comprising a pair of frictionally controlled plural speed gear reduction mechanisms.

45 17. In a mining machine of the class described, a track mounted main frame, a transversely extending guide member supported forwardly of said main frame, a cutting element associated with said guide member for movement therealong including a projecting cutter bar, a motor, and a pair of plural speed frictionally controlled drive 50 mechanisms driven by said motor for moving said cutting element along said guide member in reverse directions without reversal of said motor and for independently moving said cutter bar about a vertical axis in reverse directions without reversal of said motor.

55 18. In a mining machine of the class described, a track mounted main frame a transversely extending guide member supported forwardly of said main frame, a cutting element associated 60 with said guide member for movement therealong including a projecting cutter bar, a motor, and plural speed frictionally controlled drive mechanisms driven by said motor for moving said cutting element along said guide member in reverse directions without reversal of said motor and for

independently or simultaneously moving said cutter bar about a vertical axis in reverse directions without reversal of said motor comprising a pair of plural speed frictionally controlled gear reduction devices and reverse gearing associated therewith. 5

19. In a mining machine of the class described, a track mounted main frame, a transversely extending guide member supported forwardly of said main frame, a cutting element associated 10 with said guide member for movement therealong including a projecting cutter bar, a motor, and plural speed frictionally controlled drive means driven by said motor for moving said cutting element along said guide member in reverse directions without reversal of said motor and independently moving said cutter bar about a vertical axis in reverse directions without reversal of said motor comprising frictionally controlled plural speed planetary gear reduction mechanisms and 15 reverse mechanisms associated therewith.

20. In a mining machine of the class described, a track mounted main frame, a transversely extending guide member supported forwardly of said main frame, a cutting element associated 25 with said guide member for movement therealong including a projecting cutter bar, a motor, and plural speed frictionally controlled drive means driven by said motor for moving said cutting element along said guide member in reverse 30 directions without reversal of said motor and independently moving said cutter bar about a vertical axis in reverse directions without reversal of said motor comprising a frictionally controlled plural speed planetary gear reduction device 35 driven by said motor for moving said cutting element along said guide member, another frictionally controlled plural speed planetary gear reduction device driven by said motor for moving said cutter bar about a vertical axis and reverse 40 gearing associated with each of said planetary gear reduction devices.

21. In a mining machine, a track mounted main frame, a horizontally disposed transversely extending guide member supported forwardly of 45 said main frame, a cutter head mounted on said guide member for movement therealong, a cutter bar supported on said cutter head for vertical movement with respect thereto in a plurality of parallel planes for cutting a kerf on the mine 50 bottom below the level of the track or at various elevations with respect thereto, said cutter bar being pivotally movable with respect to said cutter head about a vertical axis independently of movement of said cutter head along said guide 55 member.

22. In a mining machine, a track mounted main frame, a horizontally disposed transversely extending guide member supported forwardly of said main frame, a cutter head mounted on said 60 guide member for movement therealong, a cutter bar supported on said cutter head for vertical movement with respect thereto in a plurality of parallel planes for cutting a kerf on the mine bottom below the level of the track or at various 65 elevations with respect thereto, said cutter bar being pivotally movable with respect to said cutter head about a vertical axis independently of or simultaneously with movement of said cutter head along said guide member for guiding said 70 cutter bar to form a substantially straight kerf along the working place.

23. In a mining machine, a track mounted main frame, a horizontally disposed transversely extending rectilinear guide member supported 75

forwardly of said main frame, a cutter head mounted on said guide member for movement therewith, a cutter bar supported on said cutter head for vertical movement with respect thereto for cutting a kerf on the mine bottom below the level of the track or at various elevations with respect thereto, and drive means self-contained within the machine for moving said cutter head along said guide member and for independently 10 moving said cutter bar about a vertical axis including plural speed frictionally controlled means.

24. In a mining machine, a track mounted main frame, a horizontally disposed transversely extending rectilinear guide member supported forwardly of said main frame, a cutter head mounted on said guide member for movement therewith, a cutter bar supported on said cutter head for vertical movement with respect thereto 20 for cutting a kerf on the mine bottom below the level of the track or at various elevations with respect thereto, and drive means self-contained within the machine for moving said cutter head along said guide member and for simultaneously 25 moving said cutter bar about a vertical axis including separate plural speed frictionally controlled means.

25. In a mining machine, a track mounted main frame, a horizontally disposed transversely extending rectilinear guide member supported forwardly of said main frame, a cutter head mounted on said guide member for movement therewith, a cutter bar supported on said cutter head for vertical movement with respect thereto 35 for cutting a kerf on the mine bottom below the level of the track or at various elevations with respect thereto, and drive means self-contained within the machine for moving said cutter head along said guide member and for simultaneously or non-simultaneously 40 moving said cutter bar about a vertical axis including separate plural speed frictionally controlled means.

26. In a mining machine, a track mounted main frame, a horizontally disposed transversely extending rectilinear guide member supported forwardly of said main frame, a cutter head mounted on said guide member for movement therewith, a cutter bar supported on said cutter head for vertical movement with respect thereto 45 for cutting a kerf on the mine bottom below the level of the track or at various elevations with respect thereto, and drive means self-contained within the machine for moving said cutter head along said guide member and independently or simultaneously 50 moving said cutter bar about a vertical axis at a plurality of predetermined speeds including plural speed planetary gear reduction mechanisms.

27. In a mining machine, a track mounted main frame, a horizontally disposed transversely extending rectilinear guide member supported forwardly of said main frame, a cutter head mounted on said guide member for movement therewith, a cutter bar supported on said cutter head for vertical movement with respect thereto 55 for cutting a kerf on the mine bottom below the level of the track or at various elevations with respect thereto, self-contained gear reduction mechanism for effecting rectilinear and pivotal feeding movement of said cutter bar comprising a plural speed planetary gear reduction device for moving said cutter head along said guide member and another plural speed planetary gear reduction device for simultaneously or 60

independently moving said cutter bar about a vertical axis.

28. In a mining machine, a track mounted main frame, a horizontally disposed transversely extending rectilinear guide member supported forwardly of said main frame, a cutter head mounted on said guide member for movement therewith, a cutter bar supported on said cutter head for vertical movement with respect thereto 10 for cutting a kerf on the mine bottom below the level of the track or at various elevations with respect thereto, self-contained gear reduction mechanism for effecting rectilinear and pivotal feeding movement of said cutter bar comprising a plural speed planetary gear reduction device for moving said cutter head along said guide member and another plural speed planetary gear reduction device for simultaneously or independently moving said cutter bar about a vertical axis, and means for locking said cutter 15 bar in various angular positions with respect to said cutter head.

29. In a mining machine of the class described, a base, a rectilinear guide member supported forwardly of said base, a cutting element movable along said guide member, said guide member including a fixed portion and a hinged portion and means whereby said guide member may be locked in an extended position or folded in a horizontal plane to extend along the sides of said base. 25

30. In a mining machine, a base, a cutting element movable across the front of said base, and means for supporting said cutting element for movement across the front of said base comprising a guide member composed of a plurality of sections hingedly connected together for movement about vertical axes and adapted to extend along the sides of said base. 35

31. In a mining machine, a base, a cutting element movable across the front of said base, and means for supporting said cutting element for movement across the front of said base comprising a guide member having a fixed central portion and hinged outer portions adapted to move about vertical axes and extend along the sides 45 of said base.

32. In a mining machine, a base, a cutting element movable across the front of said base, means for supporting said cutting element for movement across the front of said base comprising a guide member having a fixed central portion and hinged outer portions adapted to be moved about vertical axes and extend along the sides of said base, and means for locking said portions in an extended position or permitting said portions to 50 be folded along the sides of said base.

33. In a mining machine of the class described, a track mounted main frame, a transversely extending guide member supported forwardly of said main frame, a cutting element movable along said guide member, said guide member comprising a fixed central portion and hinged outer portions adapted to be moved about vertical axes and extend along the sides of said base, and means whereby either or both of said outer portions may 55 be locked in an extended position or folded along the sides of said main frame.

34. In a mining machine, a main frame, a motor on said main frame, a guide member supported forwardly of said main frame, a cutting element movable along said guide member, and means driven by said motor for moving said cutting element along said guide member comprising a telescopic shaft pivotally movable about a vertical axis transverse to its axis of rotation and 70 75

having connection with said motor and cutting element.

35. In a mining machine, a main frame, a motor on said main frame, a guide member supported forwardly of said main frame, a cutting element movable along said guide member, and means driven by said motor for moving said cutting element along said guide member comprising a telescopic drive shaft movable about a fixed vertical axis perpendicular to its axis of rotation and disposed rearwardly of said guide member, said shaft being driven by said motor and having driving connection with said cutting element.

36. In a mining machine of the class described, a track mounted main frame, a motor on said main frame, a transversely extending guide member supported forwardly of said main frame, a cutting element movable along said guide member including an elongated cutter bar, gear reduction mechanism for moving said cutting element along said guide member and for moving said cutter bar about a vertical axis, and telescopic drive connections from said motor to said gear reduction mechanism.

37. In a mining machine of the class described, a track mounted main frame, a motor on said main frame, a transversely extending guide member supported forwardly of said main frame, a cutting element movable along said guide member including an elongated cutter bar, gear reduction mechanism for moving said cutting element along said guide member and independently moving said cutter bar about a vertical axis, and telescopic drive connections from said motor to said gear reduction mechanism comprising a support pivotally supported on said main frame, and a telescopic drive shaft supported therein and connecting said motor with said cutting element.

38. In a mining machine, a transverse guide, a cutter head supported for bodily movement therealong having a pivoted cutter bar supported thereon for swinging movement about a vertical axis, a motor adapted to be in a stationary position with respect to said guide while said cutter head moves along said guide, and drive connections from said motor for swinging said cutter bar with respect to said cutter head irrespective of the position of said cutter head along said guide.

39. In a mining machine, a transverse guide, a cutter head supported for bodily movement therealong having a pivoted cutter bar supported thereon for swinging movement about a vertical axis, a motor adapted to be in a stationary position with respect to said guide while said cutter head moves along said guide, and drive connections from said motor for swinging said cutter bar with respect to said cutter head irrespective of the position of said cutter head along said guide including a telescopic drive member.

40. In a mining machine, a transverse guide, a cutter head supported for bodily movement therealong having a pivoted cutter bar supported thereon for swinging movement about a vertical axis, a motor adapted to be in a stationary position with respect to said guide while said cutter head moves along said guide, and drive connections from said motor for moving said cutter head along said guide and independently swinging said cutter bar with respect to said cutter head including a telescopic drive member rotatable about a horizontal axis and swingable about an axis perpendicular to its axis of rotation.

41. In a mining machine, a main frame, a motor on said main frame, a horizontal guide member supported forwardly of said main frame, a cutter head having a pivoted cutter bar thereon supported on said guide member for bodily movement therealong, and power operated means for swinging said cutter bar comprising a drive member telescopic within itself and pivoted for movement about a vertical axis disposed adjacent one of its ends, a drive connection between said motor and said drive member, and a drive connection from said drive member to said cutter head for moving said cutter head and cutter bar along said guide member at a feeding speed.

42. In a mining machine, a main frame, a motor on said main frame, a guide member supported forwardly of said main frame, a cutter head having a pivoted cutter bar thereon supported on said guide member for bodily movement therealong, and power operated means for bodily moving said cutter head along said guide member and independently swinging said cutter bar comprising a telescopic drive member driven by said motor and pivotally connected to said main frame to swing about a vertical axis.

43. In a mining machine, a main frame, a motor on said main frame, a guide member supported forwardly of said main frame, a cutter head having a pivoted chain carrying cutter bar thereon supported on said guide member for bodily movement therealong, and power operated means for driving said cutter chain about said cutter bar, swinging said cutter bar, and moving said cutter head along said guide member comprising a telescopic drive member driven by said motor and pivotally connected to said main frame for swinging movement with respect thereto about a vertical axis.

44. In a mining machine of the class described, a track mounted main frame, a motor on said main frame, a horizontally disposed transversely extending guide member supported forwardly of said main frame, a cutter head mounted on said guide member for movement therealong, a cutter bar supported on said cutter head for pivotal movement with respect thereto, plural speed frictionally controlled gear reduction mechanism for moving said cutter head along said frame and independently or simultaneously moving said cutter bar about a vertical axis, and drive connections from said motor to said gear reduction mechanism comprising a pivotally mounted telescopic drive connection from said motor to said cutter head and gear reduction mechanism.

45. In a mining machine, a truck, a motor on said truck, a transverse guide extending across the forward end thereof, and wholly supported thereby, a cutter head wholly supported by said guide for movement therealong, a pivoted cutter bar having a cutter chain movable thereabout supported by said cutter head for swinging movement with respect thereto about a vertical axis, power connections from said motor for driving said truck and other power connections from said motor for moving said cutter head along said transverse guide, driving said cutter chain and independently swinging said cutter bar about its axis of pivotal connection to said cutter head comprising a telescopic drive shaft pivotally supported on said truck for movement with respect thereto about a vertical axis.
